BUBBLE LEVEL

Todd Harris, Stony Brook, N. Y.

Application October 8, 1951, Serial No. 16,874

Term of patent 14 years

(Cl. D52—1)

To all whom it may concern:

Be it known that I, Todd Harris, a citizen of the United States, residing at Stony Brook, in the county of Suffolk and State of New York, have invented a new, original, and ornamental Design for a Bubble Level, of which the following is a specification, reference being made to the accompanying drawing, forming a part thereof.

Figure 1 is a top plan view of a bubble level showing my new design;

Figure 2 is a side view of the bubble level;

Figure 3 is a bottom view of the bubble level;

Figure 4 is an end view as viewed from the left of Figure 2; and

Figure 5 is an end view as viewed from the right of Figure 2.

I claim:

The ornamental design for a bubble level, substantially as shown.

TODD HARRIS.
